METHOD OF MAKING PEN NIBS

John A. Shea, Jersey City, N. J.

Application February 28, 1940, Serial No. 321,218

3 Claims. (Cl. 113—32)

This invention relates to the manufacture of fountain pen nibs by automatic machinery, and more particularly it relates to an intermediate step in such manufacture.

The making of pen nibs and methods of making the same have been described in my earlier patents, Nos. 2,195,430, dated April 2, 1940, and 2,208,477, dated July 16, 1940, respectively, and as before stated, this particular invention is directed to an intermediate step in a process of that kind.

More particularly, the present invention has for its object to form a flat winged tip into a V-shape winged tip, and the invention also has for its object to close the V winged tip, preparatory to its next step in the process. The object of this invention is to mold the wings of a flat wing tip pen into writing condition by a V-shaping and a final cold forging or molding, and at the same time additionally hardening and smoothing the same. Furthermore, the invention consists of an improved device for making the foregoing winged tips.

The invention will be more fully described hereinafter, embodiments thereof pointed out in the drawing, and the invention will be finally set forth in the claims.

In the accompanying drawing:

Figure 1 is a plan view of part of the improved device supporting a winged tip in flat form;

Figure 2 is an end view thereof;

Figure 3 is an end view showing the next step in the operation of the device;

Figure 4 is a plan view after the operation in Figure 3 has been completed;

Figure 5 is a sectional view of another improved device which has for its object to bring the V shape nib tip together so that the wings are approximately parallel with each other, this view being taken on the line 5—5 of Figure 4;

Figure 6 is a similar view showing the end of the operation with the wings parallel with each other;

Figure 7 is a section partly in elevation of the winged tip shown in side view, taken on the line 7—7 of Figure 6;

Figure 8 is a view of the top member shown in Figure 5;

Figure 9 is a sectional view of the top member shown in Figure 8, taken on the line 9—9 of Figure 8;

Figure 10 is a section taken on line 10—10 of Figure 9; and

Figure 11 is a plan view of another nib end

showing the winged tips provided with an intermediate slot.

Similar characters of reference indicate corresponding parts throughout the various views.

Referring to the drawing, and more particularly to Figures 1 to 4 and Figure 11, the nib end 15 has two winged tips 16 and 17 in the same plane with each other and with the nib 15. This is the form in which the nib has been made up to this stage of the automatic manufacture.

The exterior contour of the winged tip 16 and 17 has been hardened as shown by the lines 18, and at the same time all the corners and edges have been rounded and smoothed.

In Figure 1 is shown one form of nib end in which the two winged tips 16 and 17 form one integral part.

In Figure 11 another form is shown in which the nib 15a is provided with two spaced winged tips 16a and 17a with an intermediate slot 19 therebetween. The configuration of this slot 19 may be varied or changed from that shown in Figure 11. The winged tips have also been rounded, smoothed and hardened as indicated by the lines 18a. They can extend to the apex.

The object of the next step of this automatic process of making fountain pen nibs by automatic machinery is to give the winged tips 16 and 17 a preliminary shape in the form of a V. This is done by means of particular devices such as shown in Figures 2 and 3. The base member 32 of this device consists of two platform portions 19 and 20, each of which supports one winged tip. Between these platform portions 19 and 20, a cut out 21 is provided which has inclined sides 22 and 23, converging toward each other and merging into other inclined sides 25 and 26, having a sharper angularity in respect to a vertical line than the inclination of the lines 22 and 23.

Above the base members 19—20 as just described and above the superimposed winged tips placed thereon is a plunger member 27 having a narrower portion 28 terminating in a V-shaped end portion 29, the apex 30 of the V being sharp or knife-like. The member 27 is suitably engaged by a plunger of a punch of any well known construction, not shown, and the member 27 is thereby caused to descend and have its sharp knife-like edge 30 engage the median line between the two winged tips 16 and 17, and in the further downward movement of the member 27 the winged tips are forced into the cut out 21 and the exterior sides of the winged tips caused to move along the inclined surfaces 22 and 23, and 25 and 26, until the winged tips are formed

into a V shaped configuration as shown in Figure 3 when looking at the end thereof, or shown in Figure 4 when looking downwardly from the top thereof.

If an integral winged tip, such as shown in Figure 1, be used, the metal between the winged tips 16 and 17 will be scored as shown by the score line 33 in Figure 4.

What has been described in connection with the form of winged tips shown in Figure 1 takes place also when a winged tip such as shown in Figure 11, is acted upon. In this case the score line 33a will be also present.

Having shaped the nib tips into the preliminary and intermediate V formation, the next operation by an adjacent die is to bring the winged tips into parallel position in respect to each other. By virtue of the action of the member 27, with its compressing end member 29, the lower surfaces of the winged tips 16 and 17 are rounded as shown in Figure 3 by the character 35, it being noted in Figure 3 that a gap 36 in the base member 32 remains unfilled by any metal. To provide a surface for this rounded portion 35, the device shown in Figure 5 has a base member 37 with a rounded recess 38, the configuration of which is substantially the same as the rounded portion 35 of the winged tips. The upper member of the device shown in Figure 5 indicated by 39, is provided with two recesses 40 and 41 with a partition 42 therebetween. These recesses 40 and 41 are each curved with their exterior end portions flush with the lower surface 43 of the upper member 39, whereas the inward ends of the curved portions where they merge in the partition 42 are inset from the surface 43 of the member 39. This arrangement of the ends of the recesses is for the purpose of having the outermost ends of the curved portions engage the outermost ends of the winged tips as shown in Figure 5. When the upper member 39 is moved downwardly in the direction of the arrows 44, by a suitable plunger of a suitable punch, not shown, the two outermost ends of the winged tips 16 and 17 are brought into contiguous relationship or parallel with each other as shown in Figure 6. By the moving of the outermost ends of the winged tips along the curved recesses 40 and 41 into their parallel positions, the pressure thereby exerted and the downward pressure of the member 39, with its partition or ridge 42 between the winged tips, serves to smooth and round and additionally harden the contiguous edges and inside of the winged tips. In other words, the upper part of the space between the winged tips, the partition or ridge 42 serves to smooth out these portions at the end of the space. When these two winged tips have been brought together and the ridge or partition has acted upon the curved portions at the end of the space between the winged tips, these curved portions are smoothed and hardened by the pressure exerted by the ridge or partition 42. This is clearly shown in Figure 6, and when the winged tips have been brought into the position in Figure 6, they are ready to be slotted by shearing in the next step of the automatic manufacturing process.

By referring to Figure 8, it will be seen that this partition or ridge 42 terminates in two curved portions indicated by 48 and 49, and these also have a smoothing effect upon the end of the winged tips. The base member 37 has a rib 50 as shown in Figures 4 and 7, and when this rib acts upon the lower part of the winged tips, 70

it leaves a smaller recessed portion 51, as shown in Figure 7.

Heretofore, wing tip pens have been formed in a two-stage bending operation, being first bent in the form of a V on two bend lines by a blunt edge punch. The wings were then closed by bending again on the same two lines utilizing jaws and bending from the sides for this purpose. This method naturally puts undue stress and strain on the tips, because of being bent twice on the same lines. And it has not been possible to bend metals such as stainless steel of a very hard and brittle nature containing approximately 4% moly without cracking.

Only one bend line is utilized which forms the apex of the V when the tip with its wings is bent, by pressure applied to the face of the nib. The bend line is parallel with but spaced from the longitudinal axis of the pen nib, said longitudinal axis being between the face and back of the pen nib. By the bending of the flat blank the bend line on the face of the nib is compressed or lessened while the back of the tip of the nib is extended. When the original blank is thus formed into a V shape thereafter it is subjected to a cold forging molding process which completes the bending of the bend line and brings the wings at each side of the tip into a position where the wings are substantially parallel with each other. While this second bending is taking place the cold forging molding process compresses the metal of the wings with so much of the tip as is common to both of the wings and thereby the newly formed tip of the pen is coined or molded and brought into a different state than if the wings were merely bent into position. By the method described in which the preliminary V bending first takes place and thereafter the coining operation is employed, the various pressures become equalized in such a manner throughout the wings and tips that the metal is not subjected to undue stress and strain. By this method it has been possible to successfully form pen tips having a writing surface from the particularly hard and brittle 4% moly stainless steel used for the pen blanks.

Thus, it will be seen from the foregoing that applicant has devised an entirely new method of molding the flat wing tips of a pen into writing condition while at the same time additionally smoothing and hardening the same.

It will be noted that the preliminary shaping is done by a knife-like blade along only a single line, as is clearly shown by 33 in Figure 4. Prior methods of closing the wings have all utilized jaws to bend the wings in from the sides. This is impractical in a strip method such as applicant's, and therefore after the preliminary shaping, he has devised a cold-forged molding operation which has a number of distinctive and improved features. First, by discarding the old type jaws and utilizing pressure from above the wings, he is enabled to smooth the wings at the most vital point, that is, the inside of the wings where the writing is done, the improper smoothing of this part being the principal reason for the scratching of fountain pen nibs. Secondly, due to the pressure exerted in molding these wings into writing condition, and additionally smoothing the same, thus compressing the metal, they are additionally hardened, which produces a pen with greater wearing qualities and longer life. Thirdly, by this molding or cold-forging, applicant attains the effect of a lathe-ground gold iridium tipped pen nib. In carrying this out, the pen

which was bent into its initial position of a V is now closed, so as to bring the legs of the V in substantial parallel relation with each other. In other words, the V inclination is changed to a parallel relationship.

Reference is made herewith to my co-pending applications, Serial Nos. 325,105, filed Mar. 21, 1940, and 321,217, filed Feb. 28, 1940, respectively, and both to issue on the same date, and to pending application, Serial No. 357,926, filed Sept. 23, 1940.

I have described an embodiment of my invention, but it will be clear that changes may be made within the principle of the invention described, without departing from the scope of the subjoined claims.

What is claimed is:

1. In the manufacture of a wing tip pen from a flat blank of metal having a tip and lateral wings extending longitudinally of the body of the blank, the back and face surfaces of the tip and wings being in parallel planes spaced apart the thickness of the metal, with the longitudinal axis of the tip and wings spaced intermediate said spaced planes, the step which consists in subjecting the face of the tip to a pressure along a single line parallel with said axis and centrally disposed on the face of the tip, simultaneously subjecting the backs of the wings to pressures laterally inwards, the back of the tip being unopposed by any pressure, all of said pressures acting to shape the flat tip and wings to a V shaped member, with the metal along said bend line on the face compressed and the metal on the back of the tip extended, then subjecting the back of said tip and wings to pressures moving the wings towards each other to substantial parallelism, and at the same time subjecting each of the free ends of the wings to a pressure towards its base and the bent tip common to both wings, for compressing the material of the wings.

2. In the manufacture of a wing tip pen from a flat blank of metal having a tip and lateral wings extending longitudinally of the body of the blank, the back and face surfaces of the tip and wings being in parallel planes spaced apart the thickness of the metal, with the longitudinal axis of the tip and wings spaced intermediate

said spaced planes, the step which consists in subjecting the face of the tip to a pressure along a single line parallel with said axis and centrally disposed on the face of the tip, simultaneously subjecting the backs of the wings to pressures laterally inwards, the back of the tip being unopposed by any pressure, all of said pressures acting to shape the flat tip and wings to a V shaped member, with the metal along said bend line on the face compressed and the metal on the back of the tip extended, then subjecting the back of said tip and wings to pressures moving the wings towards each other to substantial parallelism, simultaneously subjecting each of the free ends of the wings to a pressure towards its base and the bent tip common to both wings, for compressing the material of the wings.

3. In the manufacture of wing tip pens from a flat blank having laterally extending wings in the plane of the blank at the end intended to form the writing tip, one face of the blank being the front and the other face of the blank being the back, which consists in subjecting said tip with its lateral wings to a pressure to bend into parallelism with each other to bring the front faces of the wings to a position adjacent each other, and to bring the free ends and the bent portion at the back into substantially a vertical line at right angles to the face of the flat blank, the said bent back being rounded by such bending, and subjecting said wings to a compression action along said vertical line, applied only to the adjacent free ends of the wings and to the rounded exterior back end of the tip, to restrainingly compress the metal at the free ends of the wings and at the back end of the tip, with the longitudinal outer sides of the wings unrestrained and free to expand to form an oval form, whereby the wings are reduced in size in the direction of said straight line from each of the free ends to said rounded back end, and said free ends and rounded back end are cold forged hardened to form the writing surfaces of the wings.

JOHN A. SHEA.
